UNITED STATES PATENT OFFICE.

LUDWIK STAWICKI, OF MUSKEGON, MICHIGAN.

ASH-SIFTER.

1,219,600.

Specification of Letters Patent. Patented Mar. 20, 1917.

Application filed March 18, 1916. Serial No. 85,033.

To all whom it may concern:

Be it known that I, LUDWIK STAWICKI, a subject of the Czar of Russia, residing at Muskegon, in the county of Muskegon and 5 State of Michigan, have invented certain new and useful Improvements in Ash-Sifters, of which the following is a specification.

This invention relates to new and useful improvements in ash sifters.

10 The primary object of the invention is the provision of a device serviceable for household use whereby ashes may be sifted by a clean and sanitary method, the combustible contents being easily separated for 15 use.

A further object of the device is the provision of an ash sifter having a neat appearance and being easily operated while preventing the escape of dirt and dust during 20 the sifting operation, the partially burnt coal being readily removed for reburning.

A still further object of the device is the provision of an ash sifter having two parts which may be readily separated, the device 25 being cheap and easy to manufacture from sheet metal and being highly efficient in its operation and non-combustible in structure.

With these general objects in view and others that will appear as the nature of the 30 invention is better understood, the same consists in the novel combination and arrangement of parts hereinafter fully described, illustrated in the accompanying drawings and then claimed.

35 In the drawings forming a part of this application and in which like designating characters refer to corresponding parts throughout the several views:—

Figure 1 is a central vertical sectional view through the device as positioned during the sifting operation.

Fig. 2 is a front elevation thereof.

Fig. 3 is a view similar to Fig. 1 with the elements normally arranged and with the 45 ash tray partially removed, the bail thereof being shown elevated in dotted lines.

Fig. 4 is a perspective view of a forward corner portion of the device with the slide door partly opened.

50 Fig. 5 is a vertical transverse sectional view of the device taken upon a plane at right angles to the plane of section of Fig. 1, the sieve being shown partially tilted by dotted lines.

55 Fig. 6 is a horizontal sectional view taken upon line VI—VI of Fig. 3.

Fig. 7 is an enlarged detail sectional view of a rear portion of the sieve member inclosing the receiving tray therein, and

Fig. 8 is a detail sectional view taken 60 upon line VIII—VIII of Fig. 3.

The present device being specially designed for household use in the operation of sifting mixed ashes and cinders for the purpose of separating the same to allow the 65 cinders so cleaned to be employed for burning, a dust-proof substantially cubical casing 10 is employed for containing the operative mechanism hereinafter set forth and adapted to prevent the escape of ashes and 70 dirt during the sifting operation.

A pan shaped sieve or sifting member 11 is revolvably mounted upon a horizontal axis within the casing 10 by means of a shaft 12 secured longitudinally of the bottom 13 of 75 the said sieve and having its inner end 14 journaled in a perforation 15 in the rear wall 16 of the said casing while the forward end of the shaft 12 rests in a central socket 17 in the lower edge 18 of a door opening 19 80 in the forward side 20 of the said casing. A slide door 21 is arranged for the said door opening 19 and has a coöperating socket 22 in its lower edge for overlying the shaft 12, whereby the sockets 17 and 22, each of which 85 is substantially semicircular, form a journal bearing for the said forward end of the sieve shaft 12. A hand operating lever 23 is pivoted as at 24 to the outer free end of the shaft 12, the said lever being retained in 90 its normally lowered position by means of a U-shaped spring clip 25 mounted adjacent the bottom of the front wall 12 and centrally thereof. The sieve 11 has a foraminous covering 26 upon the side thereof opposite its 95 bottom 13 while the forward end of the said sieve is normally opened adapted for the sliding reception of a receiving tray 27 of substantially the same configuration as the sieve 11 but of slightly less dimensions, it 100 being understood that the said tray is open at the top thereof being provided with an edge bead 28 which is positioned adjacent the sieve covering 26 when the tray is operatively arranged within the sieve, as best 105 illustrated in Fig. 7 of the drawings.

A swinging bail 29 is carried by the tray 27 having its free end slightly bent for overlying the forward edge of the said tray when the bail is in its inoperative position which 110 allows such free end to wedgingly engage the forward edge of the sieve covering 26

for assisting to retain the tray within the sieve. Stop washers 30 are carried by the shaft 12 adjacent its opposite ends for bearing against the rear and front walls of the casing 10 when the sieve is arranged therein, while it will be understood that when the device is normally positioned as shown in Fig. 3 of the drawings, the door 21 may be opened by means of its handle 31 for allowing the tray 27 to be withdrawn from the sieve by means of the bail 29 for emptying the cinders from the tray and refilling the same with cinders and ashes. The tray is then re-positioned in the sieve 11 by sliding the same therein and upon lowering the top 21, the lever 23 is detached from the clip 25 and upon being released, the sieve 11 reverses its position by reason of its own weight with the foraminous covering 26 arranged downwardly and whereupon lateral impulses imparted to the lever 23 results in sifting the ashes from the tray 27 through the sieve covering 26 and into the ash box 32 at the bottom of the casing 10.

The said ash box 32 is slidably arranged upon the casing bottom 33 and has a hand-hold knob 34 whereby the box is readily removed for emptying the ashes therefrom and then re-inserted in the casing for further use during the sifting operation. A handle 35 is pivoted to the top of the casing whereby the entire device may be readily carried whenever desired.

It will thus be apparent that a handy device for readily sifting ashes is arranged

presenting an unobjectionable appearance and preventing the escape of any material during the sifting operation, it being noted that substantially the entire structure is formed of sheet metal, the device being absolutely fire-proof. 40

While the form of the invention herein shown and described is what is believed to be the preferable embodiment thereof, it is nevertheless to be understood that minor 45 changes may be made in the form, proportion and details of construction without departing from the spirit and scope of the invention as hereinafter claimed.

What I claim as new is:—

An ash-sifter, including a sieve having a foraminous covering, said sieve having fixed centrally to its bottom, a shaft journaled in position for reversing the sieve bottom-upward as in presenting the sieve-covering 55 downwardly in performing the sifting operation, said shaft having pivotally connected to one end thereof a handle, means for the retention of said handle in position as against the casual rotation of said shaft, 60 and a tray insertible within said sieve, one end of the latter being open therefor, said tray having pivotally connected thereto a bail having its free end bent for overlying the forward edge of said tray and wedgingly 65 engage the forward edge of the sieve to provide for aiding the retention of the tray within the sieve.

In testimony whereof I affix my signature.
LUDWIK STAWICKI.
